CLARICE J. POTTS, OF WINFIELD, KANSAS

AUTOMATIC WINDMILL CONTROL

Application filed September 6, 1930. Serial No. 480,254.

This invention relates to improvements in automatic controls preferably adaptable for use in automatically throwing into and out of gear of a windwheel or the like, but which 5 may be employed in a variety of mechanisms for the accomplishment of work.

The primary object of the invention is the provision of an automatic windmill control which is relatively simple and will efficiently and automatically throw into or out of gear the windwheel depending upon the quantity of water within a reservoir or tank.

Other objects and advantages of this 15 invention will be apparent during the course of the following detailed description.

In the accompanying drawings, forming a part of this specification, and wherein similar reference characters designate corresponding parts throughout the several 20 views,

Figure 1 is a side view of the improved control, showing its application to a windmill and its operative assemblage with a liquid level controlled float.

Figures 2 and 3 are sectional views taken through the improved automatic control showing inoperative and operative positions of a trip lever.

Figure 4 is a plan view of the improved control.

Figure 5 is an enlarged fragmentary view, partly in section, showing more particularly the mounting and details of certain ratchets or detents of the control.

Figure 6 is a side elevation of the lower part of the control opposite to the side illustrated in Figure 1.

In the drawings, wherein for the purpose of illustration is shown only a preferred embodiment of the invention, the letter A may generally designate the improved control, which may be operatively associated with a windmill B, being mounted upon the derrick structure C thereof and operatively connected with the pump rod D. The automatic control is operatively connected with a float F operative upon liquid within a tank G wherein the water is replenished incident to 50 operation of the windmill B; the automatic

control A being connected by means of a flexible rope or cable H with some part of the windmill, such as a clutch or other mechanism which will render the windmill inoperative for the pumping of the rod D when the water in the tank G has reached a predetermined level.

The automatic control mechanism A preferably consists of a substantially U-shaped frame 10, which comprises upstanding legs 11 and 12 connected at their lower ends by a cross piece 13 suitably apertured for receiving bolts 14 by means of which the frame may be connected to a cross bar or platform 15 of the derrick C or any other frame structure on which the control is mounted. The upper ends of the legs or standards 11 and 12 rotatably support a shaft 16 upon which a drum 17 is mounted and keyed thereto at 18. The drum 17 has one end of the flexible cable H connected therewith for winding thereon in the manner of a windlass, as shown at 20 in Figure 4.

The shaft 16 has also keyed thereon at one end of the drum 17, between an end of the latter and the leg 12 a ratchet wheel 25, keyed at 26 in place on said shaft.

Rockably mounted upon the shaft 16 is a lever 30, which is bifurcated at the end pivoted on the shaft 16; providing spaced parallel lengths 31 and 32 which straddle and receive the ratchet wheel 25 therebetween, as shown in Figure 4, and which are apertured for the free rotatable reception of the shaft 16 therein. The lever 30 at its free end is provided with a slot 35 which is connected by means of a pin 36 to the pump or polish rod D of the windmill. At the opposite side of the shaft 16 from the polish rod connection, the lever 30 has the portions 31 and 32 connected by means of a spacing block 40, shown in Figure 5, riveted or bolted in place at 41. This block 40 has a detent 42 pivoted at 43 in place upon the block; the block having a rigid extension 44, between which, and the lever 42, is disposed a spring 45 under compression and normally urging the detent or pawl 42 against the teeth of the ratchet wheel 25. This detent 42 is provided with lateral extensions 47 at the free end thereof, against

one of which the trip lever 50, to be subsequently described, may be engaged for throwing the pawl out of engagement with the ratchet wheel 25.

A second detent operates upon the ratchet wheel 25; a support 55 being welded, brazed, or otherwise secured to the cross bar 13 of the frame 10 near the leg 12; the same being for the same purpose as the block 40, and being disposed at the opposite side of the frame 10 from the handle of the lever 30. It extends upwardly divergent with respect to the leg 12 and at its upper end pivotally supports an upwardly extending pawl or detent 57 which has a socket pivot at 58 in the support 55. The support 55 has a reduced extension 60 for supporting a compressed spiral spring 61 which engages against the detent 57 and forces the latter into engagement with the teeth of the ratchet wheel 25. The detent 57 is provided with lateral extensions 65 at the free end thereof, for engagement by the trip lever 50. The trip lever 50 is pivoted at 70 upon the inside of the frame leg 12, and extends upwardly, having a semi-circular arcuated part 71 the inner edge of which is offset so as to miss the shaft 16, the outer edge 72 of which is adapted to abut against the adjacent extensions 47 and 65 of the pawls or detents 42 and 57 respectively, for throwing them out of engagement with the ratchet wheel 25 at a time when the lever 50 is pulled to permit unwinding of the cable H from the drum 17.

As applied to the windmill, the frame 10 is of course rigidly connected to the derrick C, and as above mentioned, the lever 30 is pivotally connected with the pump rod D, so that upon reciprocation of the latter the lever 30 will be oscillated about the shaft 16 as a pivot. The trip lever 50, should the tank G have insufficient water in it, will be held in such position as to throw out both pawls or detents 42 and 57, holding them inoperative with respect to the ratchet wheel 25, so that the effect of reciprocation of the pump rod D in oscillating the lever 30 is merely to cause it to idle in a rocking relation upon the shaft 16. As the tank G fills to the desired height or level of water, the float F arises, and through the bell crank lever 85 and connecting rod 86, the trip lever 50 will be moved to an inoperative position, out of engagement with the extensions 47 and 65. Of course, under such circumstances the springs will actuate the detents 42 and 57, throwing them into engagement with the teeth of the ratchet wheel 25. Under these circumstances it is quite apparent that the lower detent 57 serves to restrain rotation of the drum 17 in one direction, so as to permit unwinding of the cable H therefrom, and reciprocation of the pump rod D causes an oscillation of the lever 30, and incident to engagement of the pawl 42 against the teeth of the ratchet wheel 25

rotates the latter at each downstroke of the pump rod D, for causing a winding of the cable H on the drum 17. The winding of the cable H on the drum 17 will of course perform the desired operation of throwing the windmill out of operative connection with the pump rod D. This may be accomplished in a variety of ways, such as by the operation of a clutch, or the feathering of the windwheel with respect to the direction of wind.

It is quite apparent that the automatic control device A may be employed in connection with other mechanisms than windmills. For instance, it may be used in connection with belt or wire stretchers, or load binders or the like.

Various changes in the shape, size, and arrangement of parts may be made to the form of invention herein shown and described, without departing from the spirit of the invention or the scope of the claims.

I claim:

1. In apparatus for automatically throwing a windwheel out of the wind, the combination of a supporting frame, a drum rotatable on the supporting frame, a ratchet wheel rotatable with the drum, an oscillating lever freely mounted on a pivot axis aligning with the axes of the drum and ratchet wheel provided with a polish rod engaging end projecting to one side of said axes and a detent carrying end projecting to the other side of said axes, a detent pivoted on said lever at said detent carrying end for causing rotation of the ratchet wheel in one direction upon oscillative movement of the lever in one direction, a releasable detent normally engaging said ratchet wheel for preventing rotation of the drum upon movement of the first mentioned detent over the periphery of the ratchet wheel, and trip means for releasing both of said detents with respect to said ratchet wheel.

2. In automatic control mechanism of class described the combination of a U-shaped frame including upstanding legs and a cross portion connecting the lower ends of said legs, a shaft rotatably bearing in the upper ends of said legs, a drum keyed on the shaft, a ratchet wheel keyed on the shaft, an oscillating lever including a bifurcated end straddling said ratchet wheel and freely pivoted for oscillation on said shaft and movable in an oscillative relation relative to the drum and ratchet wheel, the bifurcated end of the lever extending to the opposite side of the ratchet wheel from the handle of the lever, a spring urged pawl mounted in the bifurcated end of said lever at the opposite side from the handle of the lever and urged normally against said ratchet wheel in operative engagement therewith, an extension connected with the cross portion of said frame below the ratchet wheel, a second spring urged

5 pawl carried by said extension and normally urged into operative engagement against said ratchet wheel, each of said spring urged pawls having a laterally extending arm projecting to the opposite side of the ratchet wheel with respect to said drum, and a trip lever pivoted on a leg of said frame adjacent said ratchet wheel below the shaft mounted on the frame and extending upwardly
10 and being arcuately offset about said shaft and having a convex edge in position to engage against the lateral extensions of the spring urged pawls for moving said spring urged pawls out of operative engagement
15 with the ratchet wheel substantially simultaneously upon movement of the trip lever in a direction away from said shaft.
